ENGRAVING-MACHINE.

1,271,196.

Specification of Letters Patent.

Patented July 2, 1918.

Application filed April 7, 1916. Serial No. 89,566.

To all whom it may concern:

Be it known that I, FRANK H. MOONEY, a citizen of the United States, and a resident of Toledo, in the county of Lucas and State of Ohio, have invented a certain new and useful Engraving-Machine; and I do hereby declare the following to be a full, clear, and exact description of the invention, such as will enable others skilled in the art 10 to which it appertains to make and use the same, reference being had to the accompanying drawings, and to the characters of reference marked thereon, which form a part of this specification.

15 This invention relates to engraving machines, and particularly to a machine adapted for the engraving of fountain pen barrels or the like.

The object of my invention is the provision of a machine of the character described, 20 which is simple and efficient in its construction and adapted to automatically feed a pen barrel or similar article to operative position, then to act on the article to mark or 25 embellish a predetermined design thereon; and then to discharge the marked article from the machine and to feed another article to operative marking position therein. Further objects and advantages of the 30 invention will be apparent from the following detailed description thereof.

While the invention, in its broad aspect, 35 is capable of embodiment in numerous forms, a preferred embodiment thereof is illustrated in the accompanying drawings, in which—

Figure 1 is a front elevation of a machine embodying the invention, with portions broken away. Fig. 2 is an end elevation 40 thereof, with parts broken away. Fig. 3 is an enlarged vertical section on the line 3—3 in Fig. 1, and Fig. 4 is an enlarged front view of a portion of the machine, with parts in section.

45 Referring to the drawings, 1, 1 designate the two side standards of the machine frame, and 2 a frame part which connects and rigidly spaces the standards 1, 1 adjacent to their lower ends.

50 A pair of guide members 3, 3 rises in parallel spaced relation from the machine frame, one from the top of each side standard 1, and co-operates to form a magazine or

chute for holding a plurality of work-pieces A, fountain pen barrels in the present instance, and permitting a successive gravity feed thereof to operative position in the machine, as will hereinafter be fully described. The inner side of each member 3 is vertically grooved to receive the respective end of a work piece and to guide its downward movement. The lower ends of the guide members extend a predetermined distance down between the side standards 1, 1, and the right hand member in Figs. 1 and 4, in the present instance, is provided near its lower end in the base of its guide groove with a depression or socket 4, preferably of frustoconical form, for receiving the adjacent end of a work-piece A when in register therewith, as best shown in Fig. 4.

A sleeve 5 is journaled in the left frame standard 1 in axial register with the socket 4 and fixedly carries at its outer end a worm-wheel 6, to the inner side of which is 55 fixed a templet or pattern plate 7. A spindle 8 is mounted in the sleeve 5 for rotary movements therewith and axial movements relative thereto and has its inner end projected into the guide groove of the adjacent guide 60 standard 3 and of conical form to frictionally fit into the adjacent end of a registering pen barrel to co-operate with the socket 4 to support and effect a centering of the barrel with the spindle. In order that the 65 friction between the spindle end and a work piece may be increased, it is preferable to provide the spindle end with a plurality of radiating grooves, as shown. The opening 70 through the sleeve 5 is enlarged at the inner end portion of the sleeve, as at 9, to receive a coiled compression spring 10 in encircling relation to the spindle, thereby causing the spindle to be normally urged inward in work holding position. The sleeve 5 and worm-wheel 6 are keyed together, in the 75 present instance, by a screw form of key 12.

A trip-lever 13 is pivoted intermediate its ends to the outer end of the spindle 8 transversely of the spindle axis and is fulcrumed 80 at one end to a stud 13^a at the outer side of the worm-wheel 6, at one side of its axis, for oscillation in a plane parallel to the spindle axis, and has its other end projecting beyond the peripheral edge of the worm-wheel. It is thus apparent that an outward 85

movement of the trip lever 13 will effect a withdrawal of the spindle 8 from work gripping and holding position, against the tension of the spring 10. The means employed 5 for coacting with the trip lever 13 and effecting an outward movement thereof at a pre-determined point in each cycle of operations of the machine will be hereinafter described.

The worm-wheel 6 meshes with a drive-worm 14, which is carried by a shaft 15 mounted transversely of the worm-wheel axis in a bearing 16 provided therefor on the adjacent frame standard 1. The shaft 15 is shown, in the present instance, as being provided at its rear end with a pulley 17 from which a belt may extend to any suitable source of power. The opposite end of the shaft 15 is provided with a cam-wheel 18 having a crank-pin 19 that is connected by a connecting-rod 20 to an arm 21 projecting from one side of a slide-frame 22. This slide frame is fixed, by set screws 23, to a pair of guide rods 24 and 25, which, in the present instance, are disposed in vertically spaced relation, and have the opposite ends thereof suitably mounted for horizontal sliding movements in the respective frame standards 1, 1.

A vertically disposed vibrator lever or member 26 is mounted in the slide-frame 22, and is carried for vibratory movements by the guide rod 25, as best shown in Fig. 3. The upper end of this vibrator member is provided on its rear side with an engraving point 27 which is positioned at the front of a work-piece A when in operative position and is moved lengthwise of the work-piece by the backward and forward sliding movements of the member 26 with the slide frame 22. A coiled compression spring 28 is disposed between the rear side of the vibrator member 26 and a registering portion 22^a of the slide-frame and acts on the vibrator member to normally urge 45 the engraving point 27 into contact with a work-piece. Vibratory movements are imparted to the member 26 when reciprocated with the frame 22 by reason of a finger 29 on the member 26 traveling lengthwise of a 50 vibrator shaft 30 in contact with the serrated or undulated surface 31 thereof, such surface, in the present instance, being formed by the provision of a plurality of spaced circumferentially extending ridges 55 on the shaft periphery. The shaft 30 is mounted at its ends in the respective standards 1 below the guide members 3, 3 for both rotary and axial reciprocatory movements relative to the machine frame.

60 The shaft 30 has one end projected through the respective standard 1 in which it is mounted and bearing against the working face of the templet 7, and the opposite end of the shaft receives the thrust of a 65 coiled compression spring 32, which is

mounted in the frame bearing opening 33 therewith and has its other end thrust against a thrust member 34, which is adjustable within the opening 33 to vary the tension of the spring 32. An adjustment 70 of the member 34 is accomplished, in the present instance, by the turning of a threaded stem 35, which projects out through a plate 36 secured to the frame standard 1 at the outer end of the opening 75 33. It is thus evident that the spring 32 acts to normally retain the opposite end of the shaft 30 in contact with the operating face of the templet 7 so that the reciprocatory movements of the shaft are controlled by and in conformance to the shape of the templet surface against which it bears 80

A U-shaped yoke member 37 is pivoted at the ends of its arms to the respective standard 1, as at 37^a, and has its cross-bar or crown portion disposed in front of or at the outer side of the slide frame 22 and vibrator lever 26, at the lower ends thereof. The inner side of the cross-bar of the yoke 37 is inclined throughout its length, as at 38, and such surface, when the yoke is in lowered position, is intended to coact with a stud 39 projecting from the lower end of the lever 26 and to cause a movement of the lever against the tension of the spring 28 and a consequent retracting of the engraving point 27 and vibrator finger 29 from contacting relation to an associated work-piece and to the serrated or roughened surface 31 of the vibrator shaft 30. A coiled compression spring 40 is disposed beneath the cross-bar of the yoke 37 and normally retains such yoke in elevated or inoperative relation. When the yoke is in such inoperative position the vibrator lever 26 is permitted to move under the tension of the spring 28 to place the vibrator finger 29 into operative relation to the vibrator shaft 30 and to place the engraver point 27 into position to have marking contact 100 with a pen barrel or work-piece A. 105

The cam-wheel 18 coacts at its periphery with a roller 41 carried therebeneath by the cross-bar of the yoke 37 and co-operates with the spring 40 to control the properly timed 110 raising and lowering movements of the yoke. For this purpose the cam-wheel 18 is provided with a depressed surface 18^a which, when the roller 41 is in contact therewith, permits a raising of the yoke 37 by the 115 spring 40. The position and length of the depressed portion 18^a of the cam-wheel with respect to a cycle of operations of the machine is such that the roller 41 will travel therein during the working stroke of the 120 slide frame 22, or at least a portion thereof, which stroke, in the present instance, is from right to left. When the engraver point 27 has moved a predetermined distance in vibrating contact with the work it 125 130

is released therefrom by the roller 41 moving to the raised portion of the cam-wheel, such latter position being maintained during the remainder of the working stroke, if such 5 stroke has not been finished, and during the return stroke of the slide frame, the engraver point being permitted to again drop into position to engage the work when in proper position therefor. It will be understood that the work piece is being slowly 10 turned during the engraving operation so that the successive rows of engraving are slightly spaced circumferentially of the work. The engraving stroke of the point 27 is so rapid, however, that the spiral form 15 of the engraved lines due to the continual turning of the work during the engraving operation is hardly perceptible. As the slide frame 22 reciprocates, the stud 39 will be held in sliding contact with the inclined 20 surface of the looped portion of the yoke 37 by reason of the outward pressure of the member 28 on the vibrator lever 26.

It is desirable in the engraving of fountain pen barrels to leave a portion of the 25 surface thereof plain for receiving a notation of any desired information. This is accomplished by causing the vibrator shaft 30 to make a complete rotation for each 30 cycle of operations, or in other words, during the period of operation on each work-piece A, and to provide the roughened or 35 serrated surface 31 thereof with a smooth portion 31^a, (see Figs. 3 and 4,) which extends the entire length of the stroke of the 40 engraver member, and, when in register with the vibrator finger 29, coacts therewith to prevent the engraver point 27 from moving into engraving contact with the work. 45 Rotation is imparted from the sleeve 5 to the shaft 30 through a pair of gears 42 and 43 of like size, which are respectively mounted therein.

When the machine has completed a cycle 50 of operations, or in other words, when the engraving of a work piece has been completed, the free end of the trip-lever 13, turning with the worm-wheel 6, will have moved into the path of reciprocatory movements of a trip-rod 44, projecting from the 55 adjacent side of the slide frame 22 and movable therewith, and the outer end of said trip-rod will strike against the registering end of said trip lever when the slide frame 60 is at substantially the limit of its working stroke, and will cause an outward swinging or tripping movement of said lever, such movement of the lever causing an outward drawing of the spindle 8 against the pressure of the spring 10 and a consequent releasing of the engraved work-piece to drop by gravity on the inclined delivery table 45, which at this stage in a cycle of operations is in elevated position, as shown in Fig. 3. 65 The released work-piece at this stage in the

operation only lowers a sufficient extent to permit the next work-piece in order to lower into axial register with the socket 4 and spindle 8, it being supported in such position by the subjacent engraved work piece 70 and by the table 45 until the spindle 8 has returned to work holding position. This having been accomplished, the table 45 automatically lowers to release the engraved work piece from the lower ends of the guide 75 bars 3 and to permit it to pass down the table to any suitable receiving receptacle provided therefor, after which the table 45 is again raised with respect to the guide bars 3, 3 to support a work-piece therein 80 when next released by the holding parts. The plate forming the table 45 is of resilient material to adapt it to have yielding oscillatory movements and it rises from a stationary support at one side of the machine 85 and then extends inward on an incline between the lower end of the magazine 3 and the shaft 31. The inclined portion of the table is free for vertical movements between said parts and normally stands adjacent to 90 the shaft 31, as shown by the full line position in Fig. 3. The properly timed raising and lowering movements of the table 45 are controlled, in the present instance, by the provision of a pin 46 on the inner side of 95 the gear 43, such pin at each revolution thereof moving into contact with the bottom of the table 45 at the adjacent edge thereof and effecting first a raising of the table and then permitting a lowering of the 100 same.

In the operation of the machine the operator connects the shaft 15 with driving means to effect a rotation of the worm 14 and parts connected therewith, and places a plurality 105 of work-pieces A in reclining superimposed relation in the chute or magazine formed by the bars 3, 3, and the lower one of the articles being placed in holding engagement with the recess and spindle having a centering action on the work-piece. It is preferable to have the trip-lever 13 at the beginning of its cycle of movements with respect to the trip-rod 44 when the spindle is placed in holding engagement with the work piece. 110 It will, of course, be understood that if desired the working of the machine may be started after the spindle has been engaged with the lowermost work piece in the guide chute. At each complete rotation of the cam wheel 18 the slide frame 22 will have a forward 115 and a return stroke imparted thereto and the yoke 37 will be raised during the working portion of the forward stroke, thus permitting the vibrator finger 29 to have contact with the vibrating surface of the shaft 30, and the engraver point 27 to have contact with the work-piece, the vibration imparted to the lever 26 due to the coaction of the finger 29 and shaft surface 31 causing suc- 120 125 130

cessive movements of the engraver point into and out of contact with the work so that a broken groove is formed in its surface. The reciprocatory movement of the vibrator shaft 5 30, due to its coaction with the working face of the templet or pattern member 7, causes the engraved portion of the work to assume a configuration similar to that of the working face of the templet. When the free end of 10 trip lever 13 has moved into register with the trip-finger 44 at the end of a cycle of operations of the machine, such finger will be engaged and swung outward or tripped by contact of the trip rod 44 therewith, there- 15 by effecting a withdrawal of the spindle 8 from work holding position and permitting the engraved work-piece to lower onto the table 45, which is now in raised position. At the same time the next work piece lowers 20 into working position and is supported in such position by the engraved work piece until the spindle 8 is permitted to return and remain in work holding position for the next cycle of operations of the machine. 25 The engraved work-piece is then released from the lower end of the guide bars 3 and discharged from the machine by the lowering of the table 45.

It is evident that I have provided a simple and efficient machine which is entirely automatic in its operation for successively feeding pen barrels or other work pieces to working position, engraving the same and then releasing and discharging the engraved 30 work piece from the machine, thus materially cheapening and facilitating the engraving operation of fountain pen barrels or similar articles.

I wish it understood that my invention is 40 not limited to any specific construction, arrangement or form of the parts, as it is capable of numerous modifications without departing from the spirit of the claims.

Having thus described my invention, 45 what I claim as new, and desire to secure by Letters Patent, is—

1. In a machine of the class described, a reciprocatory frame, a member carried by said frame for vibratory movements trans- 50 versely of its reciprocatory movements, means urging a movement of said member into work coacting position with respect to said frame, means operable to periodically move said member out of work coacting po- 55 sition, and means for imparting vibratory movements to the member when in work coacting position and reciprocated by said frame.

2. In a machine of the class described, 60 work holding and turning means periodically operable to move into and out of work engaging position, means for holding and guiding the movements of work pieces into position to be engaged by said holding means, an engraving member, and means

operable to reciprocate said member lengthwise of a work piece held by said first means and to periodically move said member into and out of coaction with the work.

3. In a machine of the class described, 70 means having a rotatable and axially movable work holding spindle, means for rotating said spindle, means for acting on a work piece held by said spindle, and means for moving said spindle to release a work piece 75 when the spindle has been turned a predetermined extent.

4. In a machine of the class described, a rotatable and axially movable work holding spindle, means for rotating said spindle, a 80 reciprocating work coacting member, means for reciprocating said member and means operable by movements of said member to move said spindle to release a work piece at a predetermined point in a turning move- 85 ment of said spindle.

5. In a machine of the class described, a rotatable and axially movable work holding spindle, means for rotating said spindle, a trip lever connected to said spindle, and 90 means operable to periodically trip said lever and impart a work releasing movement to said spindle.

6. In a machine of the class described, a rotatable and reciprocally movable work 95 holding spindle, means for guiding the movements of a plurality of work pieces into spindle engaging position, means for rotating said spindle, a trip lever connected to and rotatable with said spindle, and means 100 operable to act on said lever at a predetermined point in each revolution thereof to move said spindle to release an engaged work piece.

7. In a machine of the class described, 105 means for holding and rotating a work piece, a work piece engraving member mounted for reciprocatory movements in one plane and vibratory movements in a different plane, means for reciprocating said member and periodically moving it into work coacting position and means operable to impart vibratory movements of the member.

8. In a machine of the class described, 110 means operable to reciprocate a part there- of in one plane, a roughened member with which said part coacts, when reciprocated, to impart vibratory movements to the part, and means for shifting said member to vary 115 the vibrations of said part with respect to the reciprocatory movements thereof.

9. In a machine of the class described, a 120 work engraving member mounted for reciprocatory movements in one plane and vibratory moments in a different plane, a roughened part with which said member may have contact when reciprocated, whereby vibratory movements are imparted to the member, and means operable to impart pre- 125 130

determined shifting movements to said part to vary the vibrations of said member with respect to its reciprocatory movements.

10. In a machine of the class described, 5 means operable to hold and rotate a work piece, a vibrator shaft, means for rotating said work holding means and shaft in unison, a work engraving member mounted for reciprocatory movements lengthwise of 10 said shaft and vibratory movements transversely thereof, and having a part for contacting with said shaft when the member is reciprocally moved for vibrating the member, and means for reciprocating said member.

11. In a machine of the class described, a work holding and rotating means, a vibrator shaft, means for rotating said shaft in unison with said work holding means, a 20 work engraving member mounted for reciprocatory movements longitudinally of said shaft and for vibratory movements transversely thereof, said member having a part which coacts with said shaft to impart vibratory movements to the member when it is reciprocated, and means operable to reciprocate said member and to periodically move it into and out of position to have contact with a work piece and with 25 said shaft.

12. In a machine of the class described, means for holding and rotating a work piece, a vibrator shaft having a succession of circumferentially extending ridges, 35 means for rotating said shaft in unison with said work holding means, a work engraving member mounted for reciprocatory movements longitudinally of said shaft and for vibratory movements transversely thereof, 40 said member having a part which coacts with the ridges on said shaft to impart vibration to the member when it is in work coacting position and reciprocally moved, and means for reciprocating said member, 45 said shaft having a plain portion on one side thereof which, when turned into register with the coacting portion of said member, prevents a vibration of the member.

13. In a machine of the class described, 50 means for holding and rotating a work piece, a vibrator shaft, having a succession of circumferentially extending ridges, means for rotating said shaft in unison with said work holding means, a work engraving member 55 mounted for reciprocatory movements longitudinally of said shaft and for vibratory movements transversely thereof, said member having a part which coacts with the ridges on said shaft to impart vibration to 60 the member when it is in work coacting position and reciprocally moved, means for reciprocating said member, said shaft having a plain portion on one side thereof which, when turned into register with the coacting 65 portion of said member, prevents a vibra-

tion of the member, and means for imparting predetermined axial reciprocatory movements to said shaft to vary the vibrations of said member with respect to the reciprocatory movements thereof.

14. In a machine of the class described, a guide chute for holding and guiding the feed of work pieces to operative position, said chute having a work receiving recess in one side thereof, and work holding and rotating means disposed at the opposite side of said chute in axially alined relation to said recess and operable to coöperate therewith to rotatably hold a work piece in operative position.

15. In a machine of the class described, a work guiding chute, means operable to hold a work piece in predetermined position with respect to said chute and then to release the same to permit one work piece to move 85 from, and another to move into work operating position, and a delivery table disposed below the discharge end of said chute and operable to coöperate with the released work piece to support the other in position to be 90 engaged by said holding means and then to lower to permit a discharge of the released work piece from said chute, and means for periodically raising and lowering said table.

16. In a machine of the class described, 95 work holding and turning means periodically operable to move into and out of work engaging position, an engraving member, and means operable to reciprocate said member lengthwise of the work-piece held by 100 the said first means and to periodically move said member into and out of coaction with the work.

17. In a machine of the class described, 105 means having a rotatable and axially movable work holding spindle, means for rotating said spindle, an engraving member, means operable to reciprocate said member lengthwise of a work-piece held by said first means and to periodically move said member into and out of coaction with the work, and means for moving said spindle to release 110 a work-piece when the spindle has been turned a predetermined extent.

18. In a machine of the class described, 115 a rotatable and axially movable work holding spindle, means normally retaining said spindle in work holding position, means for rotating the spindle, a reciprocally movable work coacting member, means for imparting reciprocatory movements to said member, an element attached to and projecting transversely of said spindle, and means having its movements actuated by said member reciprocating means and operable to coact 120 with said element and effect a work releasing movement to said spindle when at a predetermined point in its turning movement.

19. In a machine of the class described, 130

a rotatable and axially movable work holding spindle, a longitudinally movable vibrator member, a work engraving tool, means for imparting reciprocatory movements to 5 said tool lengthwise of a work-piece held by said spindle and coöperating with said vibrator member to impart vibratory movements to said tool, and means for simultaneously rotating said spindle and imparting predetermined and axial movements to 10 said vibrator member.

20. In a machine of the class described, a rotatable and axially movable work hold-

ing spindle, a rotatable and axially movable vibrator shaft, a work engraving tool, means 15 for imparting reciprocatory movements to said tool lengthwise of a work-piece held by said spindle and coöperating with said vibrator shaft to impart vibratory movements to said tool, and means for simultaneously rotating said spindle and imparting rotary and predetermined axial movements to 20 said vibrator shaft.

In testimony whereof, I have hereunto signed my name to this specification.

FRANK H. MOONEY.
